UNITED STATES PATENT OFFICE.

DAVID H. ROYER, OF MILLMONT, PENNSYLVANIA.

CAR-COUPING.

SPECIFICATION forming part of Letters Patent No. 400,797, dated April 2, 1889.

Application filed June 27, 1888. Serial No. 278,366. (No model.)

To all whom it may concern:

Be it known that I, DAVID H. ROYER, of Millmont, in the county of Union and State of Pennsylvania, have invented certain Improvements in Car-Couplings, of which the following is a specification.

This invention relates to automatic car-couplings in which draw-bars are formed at their ends with beveled catches or hooks.

10 The aims of the invention are to simplify the parts, admit of the hooks being used either side up, as the position of the hook of the connecting-car may require, and to prevent the accidental disconnection of the parts.

15 Referring to the accompanying drawings, Figure 1 represents in perspective a single draw-head or coupling constructed on my plan. Fig. 2 is a longitudinal vertical section of the same on the line xx . Fig. 3 is a perspective view of two of the draw-bars coupled together. Fig. 4 is a perspective view of one of the draw-bars.

20 In the drawings, A represents a hollow or tubular draw-head, which may be made in any form adapted to receive and sustain the parts herein described and connected to the car in any suitable manner.

25 B represents the draw-bar consisting of a round rod or body portion, b, provided at one end with a rigid coupling-hook, b'. This hook, which is formed upon or secured rigidly to the body, presents an outer beveled surface, b², to ride against and lift the connecting-hook during the coupling action, and a vertical face or shoulder, b³, to engage with the companion hook, this particular feature being essentially the same as in other couplings of this type already known in the art. The hook is also formed with uprising cheeks or 30 sides b⁴ to assist in guiding the connecting-hook to its place and to prevent its disengagement by a lateral motion of the car. These cheeks are beveled or flare outward from each other on the inner faces toward 35 their forward end, whereby they are caused to present a converging mouth to guide the opposite hook to its place and to allow the hook to swing horizontally as the train passes around curves. The draw-bar or hook thus 40 formed has its round body portion passed through two supporting-plates, C C', mounted

in the draw-head against opposite ends of a strong spring, D, which encircles the draw-bar, as shown. These plates are free to move toward each other, but are limited in their 55 outward movement by shoulders a or equivalent stops formed upon or applied to the interior of the draw-head.

The draw-bar is provided with pins c and c', bearing against the outer faces of the supporting-plates C C', for a purpose which will presently appear. The rear plate, C, may be fixed against vertical play; but the forward plate, C', is adapted to play vertically to a limited extent within the head in order to allow a corresponding vertical play of the hook at the forward end of the draw-bar. The draw-bar is free to revolve about its longitudinal axis within the plates C C', so that the hook may be turned either side up—that is 70 to say, may be adjusted with its beveled face upward, as shown in full lines in Fig. 2, or turned upside down to the position indicated by dotted lines in the same figure—this rotation being for the purpose of engaging the 75 connecting-hook whether the latter presents its face upward or downward. It will be observed that in consequence of this capacity for revolution around a horizontal axis my coupling may be engaged with a coupling on 80 either end of the next car, it being unnecessary to observe any precaution as to the position of the coupling before the cars are brought together.

In the top of the draw-head I mount a 85 strong spring, E, which bears upon the plate C', urging the same and thereby the draw-bar downward. This spring answers a double purpose. When the hook is arranged with its face upward, as in Fig. 2, the spring causes 90 its end and flat face to rest firmly upon the top of the shoulder a' at the front of the draw-head, whereby the coupling-hook is prevented from turning over accidentally. When, on the other hand, the hook faces 95 downward, the spring acts to hold it in engagement with the opposite coupling.

In order to effect the disconnection of the coupling, I propose to combine with the draw-bars devices of any appropriate character for 100 lifting the hook which is uppermost out of engagement with the other.

In Figs. 1 and 2, F represents a vertical rod playing through a hole in the top of the draw-head, its lower end being formed into a ring which encircles the circular portion of the 5 draw-bar, while its upper end is jointed to a hand-lever, G, which is in turn jointed to the draw-head and extended laterally and of suitable form and position to be conveniently operated by the attendant.

10 The lifting device F and the connections for operating the same may be varied at will without departing from my invention, provided only they are adapted to lift the draw-bar and to permit its revolution in order to 15 reverse the position of the hook.

The operation is as follows: Two cars being brought together, with the hook of one facing upward and that of the other facing downward, one overrides the other and drops into 20 engagement therewith in the manner shown in Fig. 3. If the cars are brought violently together, the shoulders b^4 of one draw-bar will meet the corresponding shoulders of the other and serve as a buffer, whereupon the yielding 25 of the spring D will permit the plate C' and the draw-bar to yield in a backward direction. When the train is in motion, the yielding of the spring D will permit the plate C and the draw-bar to move forward to a limited extent. The spring serves, it will be seen, to 30 release the parts from strain and concussion,

both at the time of bringing the couplings together and also when the train is moving forward.

Having thus described my invention, what I 35 claim is—

1. The herein-described draw-bar, having the beveled hook b^2 , the converging side walls, b^4 , and the flat bearing-faces at the front ends of said walls to serve as buffers and limit the 40 motion of the heads as they are advanced toward each other.

2. In combination with the draw-head, the plate C, the vertically-movable plate C', the draw-head revolvable about its longitudinal 45 axis, and the spring E, acting to urge the draw-bar downward.

3. In a car-coupling, the draw-head, the two plates C C', movable horizontally therein, the plate C' being also adapted for vertical motion, the spring between said plates, and the draw-bar having its forward end provided with a hook and its rear end arranged to rotate in and slide through the two plates provided with pins or fastenings $c c'$. 50

In testimony whereof I hereunto set my hand, this 5th day of June, 1888, in the presence of two attesting witnesses.

DAVID H. ROYER.
